UNITED STATES PATENT OFFICE

121,778

DESIGN FOR A GAME BOARD

Edward J. Spilo, Chicago, Ill.

Application May 8, 1940, Serial No. 92,220

Term of patent 3½ years

To all whom it may concern:

Be it known that I, Edward J. Spilo, a citizen of the United States, residing at Chicago, in the county of Cook and State of Illinois, have invented a new, original, and ornamental Design for a Game Board, of which the following is a specification, reference being had to the accompanying drawing, forming part thereof.

I claim:
The ornamental design for a game board, as shown.

EDWARD J. SPILO.
